STAMP LAYOUT DEVICE

Abraham Palin, New York, N. Y.

Application January 9, 1951, Serial No. 205,147

2 Claims. (Cl. 33—95)

1

This invention relates to guide devices for laying out stamps during the process of mounting the stamps and more particularly to a device for use by stamp collectors in preparing layouts for mounting sets or groups of stamps.

A main object of the invention is to provide a novel and improved guide device for assisting stamp collectors in preparing layouts for postage stamps, said device being very simple in construction, providing accuracy in locating the margins or borders of stamps of various sizes, and saving substantial amounts of time in the process of mounting stamps on the pages of stamp albums and the like.

A further object of the invention is to provide an improved guide device for laying out the locations of postage stamps on the pages of an album and for ruling border lines around each stamp at the same time as the layout is being made, the device being inexpensive to manufacture, involving only a few parts, being easy to manipulate, and being durable in construction.

Further objects and advantages of the invention will become apparent from the following description and claims, and from the accompanying drawings, wherein:

Figure 1 is a perspective view of an improved stamp layout device constructed in accordance with the present invention.

Figure 2 is a cross sectional view taken on line 2—2 of Figure 1.

Figure 3 is a cross sectional view taken on line 3—3 of Figure 1.

Figure 4 is a perspective view showing the various elements of the device of Figure 1 in separated positions.

Referring to the drawings, the guide device is designated generally at 11 and comprises a generally L-shaped base member 12 on which are mounted the superimposed T-shaped members 13 and 14. The members 12, 13 and 14 are made of transparent material, such as transparent plastic material. The base member 12 has the arms 15 and 16 located at right angles to each other and having the respective inside edges 17 and 18. Designated at 19 and 20 are respective hair lines ruled on the arms 15 and 16 adjacent to but spaced from and parallel with the respective edges 17 and 18. A hair line 21 is ruled on the arm 16 forming a continuation of edge 17, and a similar hair line 22 is ruled on the arm 15 forming a continuation of the edge 18. A diagonal hair line 23 is ruled on the corner defined between the arms 15 and 16, the hair

line 23 connecting the outer corner defined by arms 15 and 16 with the inner corner defined by intersection of edges 17 and 18, as shown.

The T-shaped member 13 has a head portion 24 and a stem portion 25. As shown in Figure 4, the stem portion 25 is downwardly offset so as to be coplanar with the arm 16 when the head portion 24 is disposed on the arm 15. The shoulder defined by the downwardly offset stem 25 with respect to the head 24 is designated at 26 and is slidably engageable with the edge 17 of arm 15 to guide stem 25 for movement parallel to arm 16. The head 24 is formed with a longitudinally extending slot 27 through which extends a pair of guide bolts 28, 28 threadedly engaged in the arm 15, as shown in Figure 2, said guide bolts being provided with the enlarged knurled heads 29 which are clamping engageable with the head member 24 to lock member 13 in an adjusted position relative to the base member 12. The stem 25 has an edge 30 which faces the edge 18, and said stem 25 is inscribed with a hair line 31 parallel to and adjacent the edge 30. The member 13 is also inscribed with a diagonal hair line 32 which extends across the head portion 24, the diagonal hair line 32 being at right angles to the hair line 23 of the base member 12. Provided on the head portion 24 is a knurled upstanding boss 33 providing a means of moving the member 13 toward or away from the arm 16 when the clamping bolts 28, 28 are released.

The member 14 is provided with the head portion 34 and the stem portion 35. As shown in Figure 1, the head portion 34 is disposed on the arm 16 with the stem portion 35 transversely overlying the stem portion 25 of member 13 and being received thereon in the same plane as the head portion 24 of member 13. Head portion 34 is formed with a longitudinal slot 36 through which extend the clamping bolts 37, 37 which are threadedly engaged in the arm 16 of base member 12. The slot 36 is at right angles to the stem 35, whereby the slot guides the member 14 for movement at right angles to the direction of stem 35, the clamping bolts 37, 37 being arranged so as to guide the head portion 34 for movement longitudinally along arm 16, and consequently for movement toward and away from the arm 15. Stem portion 35 is thus guided for movement to and away from the arm 15 and is held parallel thereto. Stem portion 35 has an edge 38 which opposes and is parallel to the edge 17 of arm 15, and stem 35 is inscribed with a hair line 39 located par-

allel to and adjacent said edge 37. Designated at 39 is a diagonal hair line inscribed on the member 14 and extending diagonally across the head portion 34 of said member. Hair line 39 is at right angles to the hair line 23 on the corner of base member 12.

The inner margins of the arms 15 and 16 of the base member 12 are provided with calibrated distance scales 40 and 41, which may be in inches or other suitable units of length. Similar scales are provided on the margins of the stem portions 25 and 35, as shown at 42 and 43.

In using the device, the stamp to be located is laid on the page or sheet on which it is to be mounted face up. The bolt members 28, 28 and 37, 37 are loosened and the guide device is laid over the stamp in a position squared with respect to the page. It will be noted that a rectangular enclosure is defined between the corner portion of the base member 12 and the corners between the head and stem portions of the members 13 and 14. This space may be set to any desired size and secured by means of the bolts 28, 28 and 37, 37. When the enclosure has been set to the desired size a border or outline may be drawn indicating where the postage stamp is to be mounted on the page by the use of a pencil or by use of India ink where a permanent border or margin is desired. By marking the borders of various stamps to be mounted on a page by the use of a pencil in the manner above described, it is possible to lay out a complete page of stamps prior to actually mounting the stamps.

The device may also be employed to lay out the locations of triangular shaped stamps by setting the diagonal hair line 23 in a vertical position on the page and adjusting the positions of the stem portions 25 and 35 to correspond with the positions of the base corners of the triangular area to be laid out. When the device is used with a horizontal guide line, it will be apparent that the device may be set to the desired size and the guide lines 32 and 39 may then be utilized to set the device so that the base corners 45 of the triangle are on a horizontal line. Obviously, this procedure may also be employed to lay out diamond shaped stamps.

The hair lines 20, 19, 31, and 38 are employed in determining proper spacing between the laid out enclosures for the stamps to be mounted, the hair lines being at equal distances from the associated edges of the various arms 15, 16, 25 and 35.

The scales 42, 43, 40 and 41 make it possible to set up any desired shape or size of rectangle, triangle or diamond shaped enclosure in graduated sizes corresponding to the graduations of said scales. For example the scales may be graduated in sixteenths of an inch, whereby any combination of sizes, graduated in sixteenths of an inch may be laid out, whereby the device may be employed to cover a complete range of different sizes of stamps now in use.

While a specific embodiment of an improved layout device for postage stamps has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. An adjustable device for locating the positions of postage stamps on a page comprising an L-shaped member of flat transparent material,

a first T-shaped member of flat transparent material, a second T-shaped member of flat transparent material, means slidably connecting the head portion of the first T-shaped member to one arm of the L-shaped member for movement therealong, means slidably connecting the head portion of the second T-shaped member to the other arm of said L-shaped member for movement therealong, the stem portions of the T-shaped members overlapping and the inner edges thereof defining an aperture of predetermined size with respect to the inside corner of the L-shaped member, said second T-shaped member having an offset stem portion of flat material, the top face of said offset portion lying in the plane of the top face of the L-shaped member whereby said stem portions overlap with the adjacent faces in the same plane respective hair lines inscribed on the stem portions of the T-shaped members parallel to the edges thereof, a diagonal hair line inscribed on the L-shaped member at the corner thereof, and respective diagonal hair lines inscribed on the head portions of the T-shaped members, each of said diagonal hair lines being arranged to terminate inwardly at said aperture.

2. An adjustable ruling device for ruling postage stamp frames on a page comprising an L-shaped base member of flat transparent material having plane top and bottom faces, a first T-shaped member of flat transparent material, a second T-shaped member of transparent material, means slidably connecting the head portion of the first T-shaped member to one arm of the L-shaped member for movement along the top face thereof, means slidably connecting the head portion of the second T-shaped member to the other arm of said L-shaped member for movement along the top face thereof, the stem portions of the T-shaped members overlapping and the inner edges thereof defining an aperture of predetermined size with respect to the inside corner of the L-shaped member, respective length scales inscribed on the inside margins of the L-shaped member, said second T-shaped member having an offset stem portion of flat material, the top face of said offset portion lying in the plane of the top face of the L-shaped member whereby said stem portions overlap with the adjacent faces in the same plane, said first and second-named means comprising an elongated slot in the head of the respective T-shaped members at right angles to the respective stem portions thereof, and guide means on said L-shaped member received in said slot, whereby said T-shaped members are movable at right angles, one with respect to the other.

ABRAHAM PALIN.
